FEEDER FOR PLANERS.

1,171,957.

Specification of Letters Patent. Patented Feb. 15, 1916.

Application filed October 11, 1912. Serial No. 725,135.

To all whom it may concern:

Be it known that I, PETER J. JOECKEN, a citizen of the United States, and resident of Sheboygan Falls, in the county of Sheboygan and State of Wisconsin, have invented new and useful Improvements in Feeders for Planers, of which the following is a description, reference being had to the accompanying drawings, which are a part of this specification.

This invention relates to feeders for planing machines and has for its object to provide a feeder in which the feed rolls are located close together without the presence of supporting frames between them, such rolls being independently mounted so as to rise or fall or tilt in either direction with the irregularity of the surface of the work operated upon, remaining in positive driving connection throughout such movements to effect the feeding of the work past the cutters.

With the above and other objects in view the invention consists in the feeder for planers as herein claimed and all equivalents.

Referring to the accompanying drawings in which like characters of reference indicate the same parts in the different views: Figure 1 is a plan view of a feeder for planers constructed in accordance with this invention; Fig. 2 is a side view thereof; Fig. 3 is an end view thereof showing the ability of the feed rolls to adapt themselves to irregularities in the surface of the work; and, Fig. 4 is a sectional view of one of the feed rolls.

In these drawings 10 indicates a frame which may be of any desirable form or construction and which is preferably a rectangular casing as shown. A shaft 11 is journaled through the frame and has sprocket wheels 12 fixed thereon for driving the feed rolls by means of chains 13. The feed rolls 14 are preferably of solid metal to give them the desired weight, though they may be of other construction and each is provided with a central opening within which loosely fits a core 15. Each feed roll 14 has its own core 15, but the feed rolls of each row, of which there may be two or more, have their cores 15 vertically slidably mounted on cross bars 16 extending across the frame. These cross bars 16 are flat so as to prevent the turning of the cores 15 and fit in slots 17 which extend upwardly from the lower

edge of the core and are somewhat shorter than the said slots so that the cores are free to move vertically on the cross rods and the turning of the feed rolls on the cores does not interfere with the up and down movement of the cores. The feed rolls themselves are thus permitted to rise and fall independently of each other while being turned by the chains 13 passing around grooves in the face thereof, which grooves are provided with sprocket teeth 18 for engagement with the chains. The feed rolls which are in the row farthest from the shaft 11 have the chains pass halfway around their circumference, but the feed rolls in the intermediate row have the chains engage their sprocket teeth at the top and bottom thereof. The cross bar 16 of this intermediate row of feed rolls, because of this engagement of the sprocket teeth above and below with the driving chains, does not require the presence of means for holding it in a definite position as to its distance from the shaft 11 and this cross rod is therefore freely slideable at its ends in slots 19 at the sides of the frame, but the cross bar of the end row of feed rolls requires to be held in fixed position with relation to the shaft 11 in order that the driving chains may be kept tight and in engagement with the sprocket teeth of the intermediate row of feed rolls and while this cross bar has its ends slideable in slots 19 of the sides of the frame as with the other, it is fixed in position by having set screws 20 threaded therein, said set screws freely turning through lugs 21 projecting from the sides of the frame at the ends of the slots 19. The set screws 20 are locked in their adjustments by means of latches 22 which are pivotally mounted on the sides of the frame and are adapted to be swung into position between the side of the frame and the flat side of the square head of set screw 20 and prevent further turning of said set screw, the latch being provided with a spur 23 to engage the lug 21 and hold it in its locking position.

In operation the feed rolls are all hidden from the shaft 11 which is connected in any desirable manner with some suitable motor and by reason of their slideable cores they are permitted to follow the irregularities of the surface of the work, rising and falling with a change in thickness of the work and inclining to the right or left when the work

is of a tapering thickness as indicated in Fig. 3. Thus instead of the feed rolls having single points of contact with the work when the work is of tapering thickness they contact throughout their full length and thus more effectively operate on the work to force it past the cutters. Furthermore the feed rolls being mounted together side by side on the cross bars without swinging frames between them to space them apart there is no danger of a small strip of work finding a position beneath the feed rolls where it does not come in contact therewith and consequently there is no danger of such small pieces of work being thrown back by the cutters to injure the operator. Several pieces of work of different thickness may be fed to the cutters at the same time, the feed rolls adjusting themselves to the thickness of the work engaged by them in such a manner that the thin pieces of work as well as the thick pieces of work are positively driven.

What I claim as new and desire to secure by Letters Patent is:

1. A feeder for planers, comprising a frame, a pair of parallel cross rods thereon angular in cross section, a series of slotted cylindrical cores slidably mounted on the cross rods to have vertical movement thereon, a series of feed rolls, each rotatably mounted on one of the cylindrical cores, sprocket teeth formed in a groove in the center of the face of each of the feed rolls, a suitably driven shaft on the frame in the plane of the cross rods and parallel there-

with, sprocket wheels mounted on the shaft, chains connecting the sprocket wheels with the sprocket teeth of each of the feed rolls, the chains passing from the sprocket wheels around the feed rolls on the cross rod which is farther from the shaft and engaging the sprocket teeth of the other feed rolls in such passage, said cross rods being slidable in the frame toward or away from the shaft, and means for sliding the cross rod which is farther from the shaft to adjust the tension of the chains.

2. A feeder for planers, comprising a frame, a suitably driven shaft thereon, sprocket wheels on the shaft, chains passing around the sprocket wheels, cross rods slidably mounted across the frame in slots thereof, slotted cylindrical cores slidably mounted on the cross rods, feed rolls rotatably mounted on the cores and provided with sprocket teeth engaged by the chains, ears on the frame, set screws passing through the ears and threaded in the cross rod of the feed rolls which are farther from the shaft for adjusting the cross rod in the slots of the frame to tighten the chains, and a latch pivotally mounted on the frame adapted to fit between the head of the set screw and the side of the frame to lock the set screw in its adjustments.

In testimony whereof, I affix my signature, in presence of two witnesses.

PETER J. JOECKEN.
